UNITED STATES PATENT OFFICE.

PURCELL C. STEINMETZ AND CHARLES R. ELLIOTT, OF SAN FRANCISCO, CALIFORNIA;
SAID STEINMETZ ASSIGNOR TO VARIETY RUBBER COMPANY, OF SAN FRANCISCO,
CALIFORNIA.

WATER BAG.

Application filed July 27, 1921. Serial No. 467,960.

This invention relates to water bags for internal use. In the treatment of various disorders of the genito-urinary organs hot or cold applications have been found to be of great benefit. Hitherto there has been no safe, simple and satisfactory way of introducing hot or cold applications to these organs, and the present invention has for its object to provide a water bag of such form and construction as to permit of introduction of the same in collapsed condition into the female organs, said water bag having connections for admitting hot or cold water thereto from an extraneous source to cause the bag to be distended and assume the proper position within the pelvic cavities whereby to apply any desired temperature to the organs without allowing the water to come in direct contact therewith.

Referring to the annexed drawing in which the invention is illustrated and which forms a part of this specification:

Figure 1 is a side elevation of the invention.

Figure 2 is a cross section of the invention taken on line 2—2 of Figure 1.

Figure 3 is a side view of a modification of the invention.

The bag includes a casing 1, preferably of rubber, silk, fibre or any water-proof material, formed with a left collapsible wing or extension 2, a right collapsible wing or extension 3, an intermediate connecting band 4, which connects the wings 2 and 3, and a neck 5. A cork 6 is fitted tightly in the neck 5, through which cork extend two tubes 7 and 8, which tubes are tightly fitted in the cork. The outer end of tube 8 is fitted in one end of a rubber tube 9, the other end of which is connected to a douche bag 10. The outer end of tube 7 is fitted in a rubber tube 11. A clamp valve 12 is fitted on the tube 9 for controlling the admission of water into the casing 1 from the douche bag 10 through said tube and tube 8. A clamp valve 13 is fitted on the tube 11 for controlling the outlet of water from the casing 1 through the tube 7 and tube 11.

The modified form of our bag shown in Figure 3 has only one cylindrical bag 14 made of rubber, silk, fibre or any other water-proof material.

The casing 1 is placed in the vagina, contracted as shown in full lines in Figure 2,

with the band 4 in front of the uterus. The valve 12 is then opened and hot water, or cold, passes from the douche bag 10 through tubes 9 and 8 into the casing 1 which expands the wings 2 and 3, as shown in dotted lines in Figure 2, against the wall of the vagina, which expansion is under control of the patient by stopcocks 12 and 13.

The purpose of the modification shown in Figure 3 is to provide a contrivance to be used by the medical profession or the laity, as a convenient form for the direct application of heat or cold at their discretion.

The wings, when distended by the admission of water thereto, conform to the shape of the pelvic cavities and cause the bag to remain in place without further attention. The bag is inserted when collapsed, and, no matter what the position of the wings may be at this time, the introduction of water thereto will expand them and cause them to assume the proper position within the pelvic cavities. Owing to the presence of the centrally arranged band 4 distension of the bag between the wings is prevented, and therefore undue pressure is not exerted upon the uterus, no matter how much the wings may be distended. By using a cork at the neck of the bag the hot or cold water in the bag will be insulated from the sensitive skin and mucous membrane. The amount of distension can be regulated by the person using the bag through the control valves on the inlet and outlet tubes.

By the employment of a bag of this form whereby the water does not come in direct contact with the organs, it becomes possible to apply extremely high temperatures, or, conversely, extremely low temperatures, without any discomfort to the patient.

Having described our invention, we claim:

1. A water bag including a casing having a cylindrical neck and formed with a band integral with the neck, an elastic bag extending below the neck and on both sides of the band, means for admitting water through said neck into said bag and means for discharging the water from said bag.

2. A water bag including a casing having a cylindrical neck and formed with a band integral with the neck, an elastic bag extending on both sides of said band, means for admitting the water into said bag and

means for discharging the water from said bag.

3. A water bag including a casing having a cylindrical neck and formed with a band 5 integral with the neck, an elastic bag, a cork fitted in said neck, an inlet tube extending through said cork, and an outlet tube extending through said cork.

4. A water bag formed for internal use, 10 comprising a collapsible bag formed with two lateral extensions and a constricted cen-

tral portion, a neck formed integral with said central portion, means for admitting water through said neck, means for discharging water through said neck, and 15 means for controlling the rate of flow through both of said means.

In testimony whereof we affix our signatures.

PURCELL C. STEINMETZ.
CHARLES R. ELLIOTT.
